UNITED STATES PATENT OFFICE

2,322,480

PRESSURE-REDUCING VALVE UNIT

Cosby Donald Philipp Smallpeice and Charles Edward Curzons, Marton, near Rugby, England; said Curzons assignor to said Smallpeice

Application August 6, 1941, Serial No. 405,712
In Great Britain June 19, 1941

1 Claim. (Cl. 50—23)

This invention relates to a pressure-reducing valve unit of the kind in which the fluid to be controlled is admitted under pressure to a chamber, closed by a diaphragm, through a valve the movable element of which is spring-pressed in the opening direction and is moved in the closing direction by the diaphragm when the pressure in the chamber reaches a predetermined value.

An important object of the invention is to provide a compact unit of this kind, which will be of light weight.

A further object is to provide an inexpensive unit, of which the parts will be capable of long life before renewal becomes necessary.

A further object is to arrange the movable valve element to be carried by a tubular member which is slidably guided in the body of the unit and is attached to the diaphragm, the seat (through or past which the fluid pressure is admitted) for the valve element being to one side of the slidable member and the "opening" spring being disposed in the interior of the latter. Preferably one end of the spring acts against an adjustable stop, extending into the adjacent end of the slidable member, by means of which the fluid pressure in the chamber may be regulated.

A further object is to arrange for the end of the chamber remote from the diaphragm to be closed by a plate incorporating a reservoir for lubricant, a wick extending from the reservoir into the chamber.

A still further object is to arrange the body of the unit to be of substantially square section, one face, for example, that opposite the admission port for the fluid pressure, having the main control valve, which may, of course, be single-acting or double-acting and is preferably of the rotary type, and another face having a pressure gauge.

For a better understanding of these and other objects and advantages of the invention attention should be directed to the following description, in which reference is made to the accompanying sheet of drawings, wherein:

Figure 1 is a plan view of a unit adapted according to the invention, with the handle of the main control valve shown in the neutral position;

Figure 2 is a similar but fragmentary view, to a smaller scale, with the handle turned to an operative position; and

Figure 3 is mainly a vertical section therethrough, but with the end plate carrying the lubricating means shown in sectional elevation, the section being on the line III—III of Figure 1.

In the arrangement illustrated the unit has a 55

body 11 of substantially square cross-section, the body being open at its ends. At one of these is mounted the diaphragm 12, this being clamped against the adjacent end of the body by means of a cover plate 13 secured as by screws. The other end is closed by a plate 14 incorporating a reservoir 15 for lubricant, and extending from the reservoir is a wick 16 which hangs down into the adjacent portion of the chamber 17 in the interior of the body of the unit. On one face of the body is disposed a pressure gauge 18, whilst the main control valve 19 is arranged in an adjacent face. On the face opposite the main control valve is disposed the admission port 21 for the fluid to be controlled. This may be supplied at any convenient pressure above atmospheric—for example, say 80 lbs. per square inch—and, as will be well understood, it is the object of the unit to drop this pressure to a predetermined value which is, of course, greater than atmospheric—for example, to a gauge pressure of 5 or 6 lbs. per square inch.

In the inlet passage 22 is disposed a bush 23 providing a seat for a leather or like disc 24 which constitutes the movable element of the pressure-drop valve, this movable element being carried by a bracket 25. In Figure 3 the pressure-drop valve is shown closed. The bracket 25 is bolted at 26 to a thimble member 27, the latter and the bracket 25 serving for clamping the internal flange of a tubular slidable member 28. At its other end the latter is secured to the diaphragm 12, being flanged as shown at 29 for the purpose. The slidable member 28 is guided in an appropriate bore of the body of the unit.

Extending through the cover plate 13 and into the diaphragm end of the slidable member 28 is an adjustment screw 31 carrying a lock nut 32 and engaging a plug 33 which serves as an abutment for a compression spring 34 disposed in the interior of the slidable member and acting against the end thereof which carries the movable valve element 24. This spring is the "opening" spring, biasing the movable valve element 24 away from its seat. In such conditions the applied fluid pressure is admitted through the admission port 21 into the chamber 17 and the rising pressure therein acting against the diaphragm causes the movement of the slidable member 28 in the direction necessary to close the pressure-drop valve when an appropriate pressure is reached in the chamber. Adjustment of the value of this pressure can be effected by rotation of the screw 31 when the lock nut 32 has been released, as will be well understood.

In the present instance the end plate 14 is formed with a cup-shaped portion 35 which houses a compression spring 36 serving for biasing the movable valve element 24 in the closing direction. Obviously, the compression spring 36 is much lighter than the compression spring 24.

Moreover, the main control valve is in this instance shown as a two-way valve. Thus, in the stationary plate 37 secured as by screws against the adjacent face of the body of the unit there are two axially-extending bores 38, 39 communicating respectively with two delivery bores 40, from which the fluid at the reduced pressure can be selectively discharged. The co-acting rotary valve element 41 is shown in Figures 1 and 3 in the neutral position. It is fast with a spindle 42 carrying a handle 43, and the latter has spaced lugs 44 thereon to coat with a stop-pin 45 carried by the plate 37. Moving the handle in the appropriate direction, to bring the corresponding lug 44 against the stop-pin 45, will move the bore 46 in the rotary valve element into alignment with the axial bore 38, as shown by Figure 2, thus supplying the associated discharge pipe 40. In the meantime the other axial bore 39 will be coacting with the adjacent end of an arcuate surface groove 47 in the rotary element 41, the groove 47 communicating between its ends with an exhaust outlet 48 in the plate 37, as shown by Figure 2. Conversely, when moving the handle to bring the other lug 44 into contact with the stop-pin 45 the said one axial bore 38 will be in a position to exhaust through the other end of the arcuate surface groove 47, and the said other axial bore 39 will be in alignment with the bore 46 to receive the reduced fluid pressure.

Not only can the parts of this unit be inexpensively manufactured, but the unit is very compact and capable of working satisfactorily for a long period without attention. Obviously, it is immaterial whether it is used to control a liquid or a gaseous fluid under pressure.

What we claim as our invention and desire to secure by Letters Patent of the United States is:

A pressure reducing valve unit comprising a body of substantially cubic form and having a chamber in its interior, said chamber opening through two opposite walls of the body, a diaphragm disposed across one of the open walls of the body and closing said open wall, said diaphragm having a substantially central opening therethrough, a cover plate secured to said diaphragm carrying wall of the body and securing the diaphragm in position, a tubular member having one end secured to the diaphragm with its bore coinciding with the opening in the diaphragm and being slidably supported in said body, said body having an inlet port disposed adjacent the tubular member at one side thereof, a bracket carried by the tubular member and having a pressure-drop valve movable with said tubular member to close and open said inlet port, a second cover plate closing the other open wall of the body, a spring carried by the second cover plate and engaging the tubular member and bracket to urge the bracket and its valve to the closed position of the valve, a stronger spring disposed within said tubular member, a tension adjusting member extending through said first named cover plate and diaphragm and engaging the spring within the tubular member, said stronger spring being opposed to the first named spring and urging the tubular member, bracket and valve to the open position of the valve, said tension adjusting member extending exteriorly of the body and cover plate, said second cover plate being removably secured to the body and having a lubricant chamber therein accessible from the exterior of the body, and a wick extending through the cover plate into the body chamber.

COSBY DONALD PHILIPPS SMALLPEICE.
CHARLES EDWARD CURZONS.
